UNITED STATES PATENT OFFICE.

JAKE BERNSTEIN, OF ATHENS, GEORGIA.

SELF-RIGHTING SIGNAL POST.

Application filed July 17, 1922. Serial No. 575,718.

To all whom it may concern:

Be it known that I, JAKE BERNSTEIN, a citizen of the United States, residing at Athens, in the county of Clarke and State of Georgia, have invented a new and Improved Self-Righting Signal Post, of which the following is a specification.

This invention has reference to improvements in that type of signal posts used at 10 street crossings for guiding motor vehicular traffic and more especially to posts that are designed for returning to normal or upright position after having been struck or pushed over by a passing vehicle.

Primarily my invention has for its purpose to provide an improved construction 15 of post of the kind mentioned of a relatively simple and economical construction and in which the several parts of the post are so arranged and cooperatively combined that under ordinary usage the post will readily bend over from the vertical to any angle with respect to the normal, even to that of a right angle, when the vehicle engages it or 20 rides directly thereover, and will return to the vertical or normal position under such motion that the danger of breaking either the post proper, its connections with a fixedly held base, the electric light bulb, 25 and the wiring connections therewith is reduced to the minimum.

Another and important object of my invention is to provide a self-righting signal post in which provision is made for economically building the post and for making the flexible connections between the post proper and the base such, that undue buckling or breaking of the said flexible connections is overcome, irrespective of the lateral jars imparted to the post when struck 30 by recklessly directed and speedy vehicles.

A further object of my invention is to provide a traffic guide post in which special provision is made for mounting the signal 45 light at the top thereof in such manner that danger of injury to the light, as the post is struck and partly bent back or turned down to the horizontal limit, is reduced to the minimum, and for dismounting a broken light and replacing it with a new signal light, as conditions may make necessary.

In its more subordinate features, my invention provides an improved arrangement 50 of the flexible connections that join the bottom of the post and its base so that

in case the post is turned down to the horizontal plane, (run over, as it were, by the vehicle) the collapsed or bent down post or its connections with the base will be at a plane below the front axle of the passing 60 vehicle and out of the way of being struck by the vehicle axle.

With other minor objects in view, hereinafter apparent, my invention consists of a traffic guide post which embodies the peculiar features of construction and novel combination of parts, all of which will be fully explained in the following detailed description, specifically set out in the appended claims and illustrated in the accompanying drawings, in which:

Figure 1 is a central vertical section of my improved self-righting signal post, the partial and complete movements thereof being illustrated in dotted lines. 75

Figure 2 is an enlarged detail central section of the lower end of the device in which a slightly modified form is illustrated in the double breaking position.

Figure 3 is a detail horizontal section 80 taken on the line 3—3 on Figure 1.

Figure 4 is a detail plan view of the core half members in separated relation.

Figure 5 is a side view, a portion being in section, illustrating the manner of assembling the parts. 85

Figure 6 is a diagrammatic illustration of the relation of the improved device to a motor vehicle passing directly over the same.

Figures 7 and 8 are detail views of modified forms of the invention hereinafter specifically referred to. 90

In the practical development of my invention, the preferred embodiment of which is shown in Figures 1 to 5 inclusive, the complete post structure includes a heavy metal base 1 which has a convex top 2 that forms a bearing for the rocker member 3 which constitutes a part of the upright or wooden post body proper, the latter being flexibly connected with the base in the manner best shown in Figures 2, 3 and 5, and as presently fully explained. 95

The post body, in the preferred form of my invention, is composed of two half round sections 4—40, each of which has a semi-circular cavity 41, the said cavities extending in the direction of the length of the said sections 4—40, and which, when the said top post sections 4—40 are operatively assembled, con- 105 110

- stitute a vertical cavity in which is received a stout coil spring 5 that constitutes the tension means for maintaining the post in upright position and for restoring it to such 5 position after it has been deflected to a partially laterally tipped position, as shown in dotted lines at the left in Figure 1, or to a substantial horizontally tipped position, as diagrammatically indicated in Figure 6.
- 10 Each post section is also formed with a reduced semi-circular groove 43—44, which grooves merge with the respective main grooves in the sections 4—40 and extend from such main grooves through the upper and 15 lower ends of the sections, the lower grooves 44—44 providing, when the sections 4—40 are joined together, a reduced passage for the flexible cable 6 that connects with the lower end of the tension spring 5 and which 20 flexibly joins the post and its solid member 3 in rockable contact with the base 1, the latter, in practice, being either of sufficient weight to hold the post in a relatively fixed place as it is struck and buckled over, or it 25 may be provided with apertured flange portions for spiking it to the ground, as is clearly illustrated in Figures 1 and 2.

To provide for conveniently and flexibly joining the post to the base 1, the latter is 30 hollow, as at 11, and provided with a central passage 12, through the dome thereof, the upper end of which is preferably flared, the reason for which will presently appear.

The bottom post member 3, before mentioned, is preferably a ball-shaped solid casting to give sufficient weight to cause it to tend to hold to its seat upon the outer or dome shaped surface of the base 1 and it also provides for holding the lower end of 40 such member 3 in flexible contact with the base 1 so that the post when righting itself will freely move back into proper relation with such member 3, as it returns to its upright position, after having been partially 45 turned down or turned down to the limit of its drop movement, as indicated in Figure 1.

The wooden post section has a horizontal aperture 10 at its upper end which extends from the outside through the side thereof, (see full lines in Figure 1 and dotted lines on Figure 4) and the upper end of the opposing post section 40 has a deep slotway 45, open at the top, which merges at the inner side with the restricted vertical passage that is formed at the upper end of the post when the grooves 43—43 of the two sections are brought into register as in Figure 1.

By forming the main post of two like half sections, shaped up as shown, a very 60 simple and inexpensive post body is provided, since, when assembling the two parts into operative connection, the flexible cable 6, which is attached to a cross pin 8, that engages the hollow inner face of the base 1, can be easily threaded into the opening in the

base top and through a central passage 30 in the solid member 3, and its free end made fast to the lower end of the spring 5, and by securing the upper end of the spring 5 to a cross pin 9 that carries a wire connection 90, 70 which joins with the spring, and then pushing one end of the pin 9 into the cross passage 10, the several parts—the spring 5, cable connection 6, the head or member 3 and the post section 4—are held as a single unit 75 and in position for the ready application of the other wooden half section 40 of the post, which latter can then be applied by fitting it flatwise (see Figure 5) against the opposing post section 4, its slotway 45 receiving the projected or free end of the pin 9.

After the two wooden sections are assembled, as stated, the said two sections are held against becoming displaced,—when struck by a passing vehicle,—by a metal casing 15, whose length is somewhat more than the length of the wooden post bottom, to thereby provide a bottom annular flange-like extension 16, which seats within an annular groove 31, which surrounds a central hub-like portion 32 on the member 3 and which provides for the ready automatic resetting of the post and the head 3, upon the base 1, when the parts return to their upright position when released by the passing vehicle that deflected the post from the vertical position. 90

By referring more particularly to Figure 2 of the drawing, it will be noticed that the base connections for the post body are such that two distinct points of flexible or hinged breaks are provided at the lower end of the post to thereby readily maintain the member 3 and the post body to a relatively rigid relation when the post is but partly knocked down, as indicated by the dotted lines to the left of Figure 1 and also to provide for a double break flexure of the post when it receives hard knocks that tend to turn it down to the horizontal plane, a condition present when a vehicle runs over the post as is diagrammatically illustrated in Figure 6. 100

Another and important advantage, in providing the lower end of the post with a base or head member 3, in the nature of a solid ball, is, that the said member 3 and the post are adapted for freely tilting over the base 1 when hit from any direction. 105

When posts of larger sizes, such as are especially needed where traffic is unusually heavy are employed, to hold the post from being readily laterally displaced to the extent that excessive strains are on the cable 6, the contacting surfaces of the member 3 and the dome of the base 1 may be formed with a series of annularly stepped ribs or serrations 35 and 17 respectively, such roughened contacting surfaces of the opposing members and the weight of the member 3 particularly aiding in holding the parts together when 110 120 125 130

the post body is deflected, as shown in Figure 1.

Referring again to Figure 2 of the drawing, it will be seen the base connections 5 for the post body are such that two distinct flexible or hinge breaks are provided, one of which is between the lower end of the post body proper and the member 3 and the other between such member 3 and the base 1.

10 In the practical adjustment of the tension spring 5, it and the cable are drawn to such normal tension that under ordinary knocks or displacement of the post, the member 3 and the post remain in a relatively fixed relation and tip laterally as one body, but when the contact of a vehicle with the post is made in such manner that the vehicle must pass over the post, the post proper will separate from the member 3, that is,—bend 15 down at an angle of greater degree, with respect to the base 1, than the flexure or bend of the member 3, with reference to the said base 1, it being apparent that by providing a connection between the post and 20 the base 1 that has a double break as shown, the body of the post will readily swing down to the horizontal or even below the horizontal plane out of the way of the axles of the vehicle and thus allow for the free passage 25 of such vehicle over the turned down post.

Another and important advantage in making the double joint connection, that is,—combining the parts 1—3, and the post proper, as stated and shown, is that at no time will there exist a sharp angle bend in the cable connection, the bend being gradual and so distributed that danger of excessive buckling or snapping of the cable at the 30 twist points thereof, is reduced to the minimum.

To provide against undue rubbing of the cable 6 at the juncture of the outlet from the base 1 and the inlet to the member 3, a sleeve 19 of leather or rubber may be fitted about that part of the cable and the said member 3 suitably socketed as at 33, for the reception of the upper end of the sleeve 19 when the parts spring to their 40 vertical position.

It is understood that when setting the post and the latter is to be equipped with a signal light, a conduit 14 is provided in the street for passing therefrom the electric circuit cable 36 which extends up along the side of the cable 6 into the post body and up through the upper end of such post for connection with the signal lamp *x* in the usual way.

50 In the preferred construction shown in Figure 1, the upper ends of the post sections 4—40, when joined together, have a socket 46 in which is received a base member with an annular flange 37 that fits in the socket 55 46 flush with the tops of the post sections

4—40 and provides for the ready application of a circular guide plate 38 that fits over the top of the posts and which has a pendant annular flange 39 for fitting over the post top, the said flanges being secured by pins 70 or screws to the upper end of the casing and post sections, as shown.

The lamp *x* is fitted in the base member mentioned, and is protected by a gauze cage 50 which is secured in any way to the cap 75 plate 38.

Figure 7 illustrates a somewhat modified form of my invention in which substantially the same relation of the parts 1—3 and the post body are present as in the preferred 80 constructions shown in Figures 1, 3 and 5.

In the said modified form, Figure 7, the post proper is a solid wooden body whose lower end is cored to form a socket 47 that communicates with the lower end of a central passage 48 for the electric circuit wire that passes up to connect with the lamp *x* that is fitted in any suitable way on top of the post, as shown.

The pin 9 in the modified form is driven 90 transversely through the post and to bisect the upper part of the socket 47.

The tension spring 5 in the modified form, connects at the upper end with the pin 9 and extends down through a suitable diameter passage 49 in the rocker member 3 and down in a guide passage 96 through the top of the base 1, with its lower end joined to a pin 95 that is held across the lower end of the base passage 96, as shown.

In the said latter construction, the cable 6 is omitted since the spring 5 flexes when the post, the member 3 and the base separate, as shown.

In Figure 8 is illustrated a further modification of my invention. In this latter form, the post, has a deep socket 55 in the upper end thereof that constitutes a chamber in which is held the electric light *x*, the latter being seated and secured in any suitable 105 way in the bottom of the said socket member 55.

56 designates a lens which constitutes the top of the chamber 55 and through which the light rays from the lamp *x* are projected 110 when the parts are at the upright position, and the said lens is held in place by an annular angle rim 57 which extends over the peripheral end of the lens and is secured to the top end of the casing 15.

In this latter form of my invention, the spring 5 is held within the post with its upper end connected to an adjustable tension device, which includes a threaded member 53, the nut 54 and bracket 58 secured to the 125 post body, as shown.

The form shown in Figure 8 is intended for low or dwarf signals which are visible only a short distance to the drivers of machines.

From the foregoing description, taken in connection with the accompanying drawings, it is thought the complete construction, operation and advantages of my device will 5 be readily understood by those familiar with the art to which it relates.

My invention does away with the common type of rigid body posts whose use has been found objectionable because collisions therewith usually result in serious damage to the vehicle and the destruction of or putting the posts out of operative commission.

What I claim is:

1. In a post of the character described, a 15 rigid post body, and a ball-like member, the same having a tongue and groove engagement, a fixed base having a convex top on which said ball-like member is adapted to rest, a flexible connection between said base 20 and said rigid body, and passing through said ball-like member whereby to connect said post, said ball-like member, and said rigid body flexibly together, said ball-like body and said base having their opposing 25 faces stepped.

2. In a post of the character described, the combination with a relatively fixed base having a convex top, a post tiltably supported on the base and adapted for being laterally tilted in any direction with respect to the base, means including flexible tension 30 devices for normally swinging the post to an upright position, the said tension devices being secured at one end to the post and at the other end to the base, the said post including a solid bottom ball-like member that 35 rockably engages the convex top of the base, an articulated flexible joint between the said bottom member and the lower end of the 40 post to thereby adapt the bottom member for rocking on the base and the post body for swinging independently and laterally of the bottom member, the post body consisting of two half sections adapted for being flatwise 45 assembled, a casing surrounding the sections, the said casing including a projected base that flexibly seats onto the ball-like member.

3. In a post of the character described, 50 the combination with a relatively fixed base having a convex top, a post tiltably supported on the base and adapted for being laterally tilted in any direction with respect to the base, means including flexible tension 55 devices for normally swinging the post to an upright position, the said tension devices being secured at one end to the post and at the other end to the base, the said post including a solid ball-like bottom member that 60 rockably engages the convex top of the base, a flexible joint between the said bottom member and the lower end of the post to thereby adapt the bottom member for rocking on the base and the post body for swinging 65 independently and laterally of the bottom member.

tom member, the post body consisting of two half sections adapted for being flatwise assembled, a casing surrounding the sections, the said casing including a projected base that flexibly seats onto the ball-like member, 70 each of the post sections having a semi-circular groove that constitutes a spring receiving chamber when the two sections are assembled, one of the sections having a horizontal aperture at the upper end, the opposing section having a depressed transverse socket in its top that communicates with the aperture in the opposing section, a pin adapted for being slipped into the said aperture, means securing the upper end of the tension spring 75 to the pin, the free end of such pin fitting into the socket in the said other section when the two sections are assembled.

4. In a post of the character described, the combination with a relatively fixed base having a convex top, a post tiltably supported on the base and adapted for being laterally tilted in any direction with respect to the base, means including flexible tension 80 devices for normally swinging the post to an upright position, the said tension devices secured at one end to the post and at the other end to the base, the said post including a solid ball-like bottom member that rockably engages the convex top of the base, 85 means flexibly connecting the said bottom member with the lower end of the post to thereby adapt the bottom member for rocking on the base and the post body for swinging independently and laterally of the bottom 90 member, the post body consisting of two half sections adapted for being flatwise assembled, a casing surrounding the sections, the said casing including a projected base that flexibly seats onto the ball-like member, 95 the ends of the two post sections being shaped for receiving a signal lamp base, and means attachable to the tops of the two post sections for holding the lamp base in operative condition.

5. In a post of the character described, the combination with a relatively fixed base having a convex top, a post tiltably supported on the base and adapted for being laterally tilted in any direction with respect 115 to the base, means including flexible tension devices for normally swinging the post to an upright position, the said tension devices being secured at one end to the post and at the other end to the base, the said post including a solid bottom member that 120 rockably engages the convex top of the base, means flexibly connecting the said bottom member with the lower end of the post to thereby adapt the bottom member for rocking on the base and the post body for swinging independently and laterally of the bottom member, the said solid bottom member having a flat upper base provided with an annular groove, the lower end of the post 125 130

having an annular flange for engaging the said groove.

6. In a post of the character described, the combination with a relatively fixed base having a convex top, a post tiltably supported on the base and adapted for being laterally tilted in any direction with respect to the base, means including flexible tension devices for normally swinging the post to an upright position, the said tension devices being secured at one end to the post and at the other end to the base, the said post including a bottom member that rockably engages the convex top of the base, the said solid bottom member having a flat upper base provided with an annular groove, the lower end of the post having an annular flange for engaging said groove, said tension devices passing through an aperture through said bottom member.

7. In a post of the character described, the combination with a relatively fixed base having a convex top, a post tiltably supported on the said base top and adapted to be laterally tilted in any direction with respect to the base, said post including a body and a bottom member that rockably engages the convex top of said base, said bottom member having a flat upper face provided with an annular groove to receive a projection from said body, the said bottom member and the said base having passages, the post body having a vertically extended chamber, and tension devices including the following elements, namely: a cable that passes through passages in the said base and the said bottom member and into the chamber of said post body, a tension spring in said chamber to one end of which said cable is attached, means to secure the other end of said spring to the post body and means for securing the lower end of said cable to said base.

8. In a post of the character described, the combination with a relatively fixed base having a convex top, a post tiltably supported on the base and adapted for being laterally tilted in any direction with respect to the base, means including flexible tension devices for normally swinging the post to an upright position, the said tension devices being secured at one end to the post and at the other end to the base, the said post including a solid bottom member that rockably engages the convex top of the base, the said solid bottom member having a flat upper base provided with an annular groove, the lower end of the post having an

annular flange for engaging the said groove, the solid bottom member and the base having passages, the tension devices including a cable that passes through the passages in the base and the bottom member and into the post body, the latter having a vertically extended chamber, a tension spring in the chamber, means for connecting the upper end of the spring to the post and the lower end to the cable, other means securing the lower end of the cable to the base, the meeting ends of the passages in the bottom member and the base, and the bottom member and the post being flared.

9. A post of the character stated comprising a relatively fixed base having a convex top surface, a post including a rigid body and a ball-like bottom member, the latter adapted to rest on said convex surface, said rigid body and said ball-like member, and said body having a passage through the same, a tension device located in said passage with one end secured to the base and the other end secured to the post body, an electric signal lamp on the top of the post body and feeder wires passing through the passages in said base, said ball-like member, and said post body to said lamp.

10. A traffic indicator of the character stated comprising a convex base, a ball-like member tiltable upon the base, a rigid post tiltably supported on the ball-like member, spring tension devices that connect with the base, pass through the ball-like member and into the post, means connecting the upper end of the spring tension devices to the post, the said spring tension devices tending to normally maintain the ball-like member in the post in upright position, and to permit flexure of the post relatively to the ball-like member when the post is tilted down to a predetermined angle relatively to the ball and the base.

11. A traffic indicator device of the character stated comprising a base having a dome-shaped top, said top having a centrally disposed aperture, a centrally apertured ball-like member rockably supported on the base top, a rigid post body flexibly supported on the ball-like member, the said post having a spring tension device receiving cable, a spring tension device, means securing the upper end of the tension device to the post, said tension device including a portion that extends through the ball-like member and the base top, and means securing the said tension portion to the base.

JAKE BERNSTEIN.
